UNITED STATES PATENT OFFICE.

DAVID F. POLLEY, OF PLYMOUTH, MICHIGAN, ASSIGNOR TO MARKHAM AIR RIFLE COMPANY, OF PLYMOUTH, MICHIGAN.

MAGAZINE AIR-GUN.

No. 872,747.

Specification of Letters Patent.

Patented Dec. 3, 1907.

Application filed February 7, 1905. Serial No. 244,664.

To all whom it may concern:

Be it known that I, DAVID F. POLLEY, residing at Plymouth, in the county of Wayne and State of Michigan, a citizen of the United States, have invented certain new and useful Improvements in Magazine Air-Guns, of which the following is a specification, reference being had therein to the accompanying drawings.

10 The invention relates to air guns of the magazine type and consists in certain features of construction, as hereinafter set forth.

In the drawings, Figure 1 is a longitudinal section through a portion of the barrel. Fig. 2 is a perspective view of the shooting barrel and members forming the piston abutment detached. Fig. 3 is a perspective view of the members shown in Fig. 2 assembled. 20 Fig. 4 is a cross section on line x—x through that portion of the barrel forming the magazine; Fig. 5 is an enlarged cross section through the shooting barrel.

The general construction of the gun may 25 be of any desired type and comprises a false barrel, forming the air compression cylinder and magazine, a shooting barrel within the false barrel and a spring actuated piston for compressing the air. In addition to these 30 parts, there is a piston abutment between the magazine and cylinder for the piston and the delivery of shot from the magazine into the shooting barrel is controlled by a member operated by the piston, these elements 35 having all been present in previous constructions.

The present invention relates particularly to the construction of the abutment for the piston and, further, in the combination there- 40 with of the shooting barrel, the arrangement being such that said shooting barrel and abutment may be inserted in the rear end of the false barrel.

In particular, A is the rear portion of the 45 false barrel, in which is the piston B. C is a forward extension of the false barrel, which is of lesser diameter and within which is ar- ranged the shooting barrel D. The sections A and C are joined to each other, preferably 50 by telescoping their adjacent ends and ar- ranging a bushing E between the same, said parts being then brazed or otherwise secured to each other.

The piston abutment F is attached to the

rear end of the shooting barrel D and when 55 in place within the false barrel, bears against the annular shoulder a, formed by the inner end of the barrel C and the bushing E. The parts are held in this position by a cap G, which has a threaded engagement with the 60 outer end of the true barrel D and a shoul- dered engagement with the end of the false barrel C. Thus, when this cap is in position, the abutment F will be held in place against the annular shoulder a. 65

As has been stated, the magazine for the shot is formed by the chamber within the barrel C surrounding the shooting barrel D. The latter is provided with an aperture b at its rear end, through which the shot may be 70 successively admitted to the barrel. This aperture is closed by a tubular gate H, which is attached to the piston and projects for- ward therefrom, telescoping within the bar- rel D. When the piston is in contact with 75 the abutment F, the member H is in position to close the aperture b, but when the piston is retracted and its actuating spring com- pressed, the member H is withdrawn, so as to 80 permit a shot to enter through the aper- ture b into the barrel D, as shown in Fig. 1.

To guide the shot into registration with the aperture b, the forward portion of the abutment F is preferably slotted, the slot being of just sufficient width to permit the 85 entrance of one row of shot therein. To avoid the necessity of drilling the abutment to form this slot and also to cheapen the cost of constructing the abutment, I preferably form the latter in the following manner:— 90

c are circular disks which are of a size to fit within the barrel A and are centrally aper- tured at e to fit about the shooting barrel D. f are smaller disks fitting within the barrel C and also centrally apertured at g to fit about 95 the shooting barrel. The disks f are further provided with slots h, which extend from the central aperture g to the periphery. The abutment is formed from a plurality of each of these disks and the disks are assembled in 100 relation to each other, as shown in Figs. 1 and 3, by sleeving them upon the barrel D. When thus assembled, they are dipped into the molten solder, which sweats them to- 105 gether and to the barrel and forms a solid plug. The aperture b is then drilled in the barrel D at the inner end of the slot h, as illustrated in Figs. 1, 3 and 4. The con-

struction being as described, the abutment F and barrel D may be inserted in the rear end of the barrel A and moved forward until the disks c abut against the shoulder a and 5 the disks f fit within the barrel C. The piston B may then be inserted and in normal position bears against the abutment F, while the tubular gate H extends forward within the barrel D.

10 To load the magazine the cap G is removed and the shot is filled in to the annular space between the barrels D and C, after which the cap G is engaged with the threaded end of the barrel D and closes the magazine.

15 In operation, whenever the piston is retracted, a shot is permitted to drop from the slot h through the aperture b into the barrel D and thus the gun is always loaded when the spring is under compression.

20 By forming the piston abutment F of the disks c and f, the cost of construction is considerably reduced. This is for the reason that disks may be rapidly and inexpensively formed by stamping and quickly assembled 25 and rigidly secured to each other as has been described. If, in place of these disks, the abutment were made from a solid piece of metal, there would be a necessity for slotting and boring it, which would increase the cost 30 of construction.

In Figs. 1 and 5 is shown another feature of the construction, particularly designed to hold the shot in the shooting barrel from displacement before shooting. Heretofore difficulty has been experienced with magazine guns of this type occasioned by the rolling of 35 the shot forward before shooting. This will allow another shot to enter the shooting barrel, or to partially enter through the aperture b, with the result that when the gun is fired, the tube H will strike against the partially inserted shot, chipping off a piece thereof. In repeated operations, these 40 pieces will accumulate in the breech of the barrel, so as to eventually clog it, and necessitate taking the gun apart to clean the barrel. I have avoided this difficulty by the construction shown, in which I is a spring 45 detent secured to the barrel D and entering through a slot i, in a position just forward of 50 the aperture b. This detent is sufficiently yielding to permit the shot to pass when the gun is fired, but forms sufficient resistance to prevent the shot from moving forward in 55 the barrel by its own weight. To further insure the retention of the shot in position until the gun is fired, a recess j is formed in the lower side of the barrel, directly opposite the aperture b, so as to form a seat for 60 the shot, which will prevent its moving forward. With the devices just described, the shot entering the shooting barrel through the aperture b is held in position directly beneath said aperture, so as to completely bar, the 65 entrance of other shot or the projection of

any portion thereof into the path of the tube H. Thus, the chipping of the shot is prevented.

What I claim as my invention is:—

1. In an air gun, the combination with the 70 false barrel having a shoulder therein, of a shooting barrel, a piston abutment fixedly secured to the rear end of said shooting barrel and adapted to be inserted therewith in the rear end of said false barrel and against 75 the shoulder therein, and a cap adjustably mounted on the forward end of said shooting barrel and engaging the end of the false barrel.

2. In an air gun, the combination with a 80 false barrel comprising two sections of different diameters, secured to each other and forming an annular shoulder within the larger section of a true barrel, a piston abutment secured to the rear end of said true barrel 85 and having a portion thereof fitting each section of said false barrel, and a cap having a threaded engagement with the forward end of said true barrel, closing the end of said false barrel.

3. In an air gun, the combination with a 90 false barrel comprising two sections of different diameters, of a piston abutment therefor comprising a plurality of stamped, metallic disks of a size to fit the said sections of the 95 false barrel and rigidly secured to each other.

4. The combination with a false barrel and a true barrel therein, of a piston abutment comprising a plurality of stamped disks having central apertures for fitting about the 100 true barrel, said disks being integrally united to each other and to said true barrel and constituting a rigid member extending between the false and true barrels.

5. In an air gun, the combination with a 105 false barrel and a shooting barrel therein, of a piston abutment comprising the disks c and f, sleeved upon and rigidly secured to said shooting barrel and to each other, the disk f being provided with registering slots and 110 said shooting barrel with an aperture in registration with said slots, whereby the shot is guided through said slots and aperture into the shooting barrel.

6. In an air gun, a false barrel, a true barrel positioned therein, and forming a magazine of the space therebetween, said true barrel being provided with a lateral opening at the breech thereof, a piston abutment comprising a plurality of integrally united 120 stamped disks fitting said false barrel and sleeved upon said true barrel, one of said disks being provided with a slot in registration with the aperture on the true barrel.

7. In an air gun, a false barrel provided 125 with an internal shoulder, a true barrel within the false barrel, a piston abutment comprising a stamped disk apertured to permit the passage therethrough of the true barrel, said disk being integrally united with the 130

true barrel and constituting a rigid member extending between the false and true barrels, and means for causing a binding action between the piston abutment and the shoulder in the false barrel.

8. In an air gun, the combination with a false barrel, comprising two sections of different diameters, of a true barrel having a shot opening therein, and a piston abutment secured to the true barrel formed of a plurality of stamped metallic disks of a size to fit within the said sections of the false barrel, a portion of said disks having slots therein adapted to register with the shot opening in the 15 shooting barrel.

9. In an air gun, the combination with the false barrel having a shoulder therein, of a shooting barrel, a piston abutment carried by the rear end of the shooting barrel and adapted to be inserted therewith in the rear 20 end of the false barrel, and means for causing a binding action between the piston abutment and the shoulder in the false barrel.

In testimony whereof I affix my signature in presence of two witnesses.

DAVID F. POLLEY.
